6 Claims. (Cl. 212—145)

This invention relates to material handling apparatus and more particularly to a stabilizer unit for mobile crane apparatus and the like.

In most conventional crane apparatus the loads carried by the boom often provide a considerable overturning moment, which requires additional support than the support normally provided by the vehicle upon which the crane is supported. In the prior art, it has been the practice to provide additional stabilization for the boom by the use of various outrigger assemblies. Such outrigger assemblies generally consist of laterally extending members having means for engaging a support surface exterior of the vehicle. Most of such assemblies, however, are adapted to be fixed in a particular location. Whenever it is desired to move the crane apparatus to a new location, it is necessary to retract the outrigger assembly, move the crane apparatus to the new location, and to reset the outrigger assembly prior to proceeding with any lifting operations. Such a procedure has been found to be unsatisfactory for many operations and it further has been found to be desirable to provide a crane apparatus having sufficient stabilization to permit the apparatus to be moved from one location to another while carrying heavy loads.

Accordingly, it is the principal object of this invention to provide a novel material handling apparatus.

Another object of this invention is to provide a crane apparatus having novel stabilization means.

A further object of this invention is to provide a crane apparatus having a novel stabilization means which will provide sufficient stabilization to permit the apparatus to carry heavy loads when the apparatus is moved from one location to another.

A still further object of this invention is to provide a novel stabilization unit for a mobile crane apparatus and the like which will provide sufficient stabilization for the apparatus to permit the apparatus to carry heavy loads when the apparatus is being turned.

Another object of this invention is to provide a novel stabilization unit for a mobile crane apparatus which can readily be moved into a position to provide stabilization for the apparatus and easily adjusted in position to permit the apparatus to be moved while carrying heavy loads.

A still further object of this invention is to provide a novel stabilization unit for crane apparatus and the like, which is comparatively simple in construction, is simple to operate, and relatively inexpensive to manufacture.

Other objects and advantages of the present invention will become more apparent to those persons skilled in the art, in the following description when taken in conjunction with the accompanying drawings, wherein:

FIGURE 1 is a perspective view of an embodiment of the invention, having portions thereof broken away;

FIGURE 2 is a top plan view of the stabilization unit shown in FIGURE 1, illustrating portions of the vehicle upon which the unit is mounted in broken lines, and illustrating the unit in an extended position, also in broken lines;

FIGURE 3 is an enlarged rear elevational view of the unit illustrated in FIGURE 2, having portions thereof broken away;

FIGURE 4 is a cross-sectional view taken along line 4—4 in FIGURE 3;

FIGURE 5 is a cross-sectional view taken along line 5—5 in FIGURE 3, having a portion thereof broken away;

FIGURE 6 is an enlarged cross-sectional view taken along line 6—6 in FIGURE 5;

FIGURE 7 is a cross-sectional view taken along line 7—7 in FIGURE 6;

FIGURE 8 is an enlarged cross-sectional view taken along line 8—8 in FIGURE 3, and a figure-eight-shaped

FIGURE 9 is a cross-sectional view taken along line 9—9 in FIGURE 3, having a portion thereof broken away;

FIGURE 10 is an exploded view of an end portion of the stabilization unit.

In accordance with the broad aspects of the present invention, there is provided a stabilization unit for a mobile crane apparatus and the like, generally comprising laterally and horizontally extensible members mounted on the apparatus, wheeled units engageable with a support surface exterior of the apparatus mounted on the extensible members and fluid actuated means mounted on the extensible members for displacing selectively the wheeled units vertically into and out of engagement with the exterior support surface.

Referring to the drawings, there is shown the preferred embodiment of the present invention. FIGURE 1 illustrates a perspective view of the assembled unit, wherein there is provided a vehicle 20, having a vehicle cab 21 mounted on the front end of the vehicle chassis 22 and a crane 23 rotatably mounted on the vehicle chassis rearward of the cab 21. The crane 23 generally comprises a crane cab 24, a boom 25 pivotally connected to the crane cab and a suitable hoist mechanism 26. The vehicle chassis 22 is supported on suitable wheeled units 27 in the conventional manner. Also mounted on the vehicle chassis 22 is a stabilization unit 28.

Referring to FIGURES 2 through 4, the stabilization unit 28 is provided with a pair of longitudinally spaced, transversely disposed housing members 29 and 30, which are rigidly secured to the underside of a center frame member 31 of the vehicle chassis. The housing members 29 and 30 are disposed on either side of the wheeled units 27 supporting the vehicle chassis, and are rigidly secured to the center frame member 31 by means of bracing members 32, 33, 34 and 35. The housing member 29 is generally rectangular in cross-section, having a top wall 36, a bottom wall 37, side walls 38 and 39, and a center partition wall 40 disposed parallel to the side walls 38 and 39 to provide transversely extending, parallel channels or compartments 41 and 42. Slidably mounted in the transverse channels 41 and 42 are extensible beam members 43 and 44 which are adapted to be moved laterally with respect to the centerline of the vehicle. Similarly, the housing member 30 is provided with a top wall 45, a bottom wall 46, side walls 47 and 48, and a center partition wall 49 which provides a pair of transversely extending, parallel channels or compartments 50 and 51. The housing member 30 is provided with a pair of extensible beam members 52 and 53, which are adapted for sliding movement within the channels 51 and 50.

Rigidly secured to the outward end of each of the extensible beam members 43, 44, 52 and 53 is a fluid actuated device 54. The fluid actuated devices operatively interconnect a pair of longitudinally extending outrigger beam members 55 and 56 to the ends of the extensible beam members. Each of the outrigger beam members 55 and 56 are provided with wheeled units 57 mounted on the ends thereof, which are adapted to engage the ground or any other suitable support surface exterior of the vehicle. The fluid actuated devices are best illustrated in FIGURES 8 and 10 and generally comprise a housing member 58 having a vertically disposed side wall 59 and a top wall 60 which are mounted on an L-shaped bracket mem-

ber 61, including an upstanding wall 62 mounted on the end of an extensible beam member and a bottom wall 63 having a circular opening 64 provided therein. Mounted within the housing member 58 is a fluid cylinder 65 which is received through the opening 64 in the housing member 58 and having an annular flange portion 66, which is adapted to be secured to the bottom wall 63 of the housing member 58, by means of suitable bolts 67. Slidably mounted within the cylinder 65 is a piston 68 having a head portion 69 and a stem portion 70 which extends downwardly through a bottom opening in the cylindrical member 65. The cylinder member 65 is provided with a pair of fluid supply lines 71 and 72 which communicate with opposite sides of the piston head 69 and extend through an opening 73 in the side wall 59 of the device. As best seen in FIGURE 8, the housing member 59 is provided with a hood member 74, which substantially covers the exterior ends of the fluid supply lines 71 and 72. It will be appreciated that the exterior ends of the fluid supply lines 71 and 72 are adapted to be connected with a source of fluid under pressure with suitable controls, whereby the piston member 68 may be actuated axially in the conventional manner. It further is contemplated that suitable controls will be provided, so that each of the fluid actuated devices 54 may be operated selectively. Each of the piston stems 70 is provided with a rounded lower end as at 75, and an annular recess 76.

Referring to FIGURES 5 through 8 and 10, each of the outrigger beam members 55 and 56 is substantially elongated and has a rectangular cross-sectional configuration for the greater portion of its length. The beam members may be of any suitable construction, although box beams are preferred. As best illustrated in FIGURE 6, the end portions of the beam members are provided with axle members 77 on which there are mounted a pair of wheels 78. Bearing sleeves 79 are mounted on the axle member 77 and suitable lubricating fittings 80 are provided on the wheels for lubricating the bearing sleeves. The wheels are suitably retained on the axle member 77 by means of a retaining ring 81, which engages the hub portion 82 of the wheel and a pin 83 which is inserted in an opening through the axle member.

Adjacent each of the wheel units 57, each beam member is provided with a recess 84 in the upper surface of the beam member. As best illustrated in FIGURE 7, the bottom surface 85 of the recess is provided with an arcuate recess 86, which is adapted to seat the rounded end portion 75 of the piston stem 70. The end portion of the piston stem is retained in engagement in the arcuate recess 86 by means of a pair of transversely extending keeper plates 87 and 88, which are received within the annular recess 76 in the lower end of the piston stem 70, and which are rigidly secured by means of suitable bolts 89 to a pair of longitudinally extending, spaced plates 90 and 91 which bridge the sloped surfaces 92 and 93 of the recess 84. Preferably, the plates 90 and 91 are welded to the beam members.

Referring to FIGURES 3 and 4, the extensible beam members 44 and 43 are moved laterally relative to the centerline of the vehicle by means of a pair of fluid actuated devices 94 and 95. The fluid actuated device 94 comprises a fluid cylinder 96 pivotally connected to a bracket member 97 mounted on an upstanding wall 98 of an open-ended housing member 98a secured to the housing member 29, and a piston member 99 which is pivotally connected to a rearwardly extending bracket member 100 mounted on the housing member 58 secured to the extensible beam member 44. Similarly, the fluid actuated device 95 comprises a fluid cylinder 101 which is pivotally connected to a bracket member 102 mounted on the upstanding wall 98, and a piston member 103 which is pivotally connected to the upstanding plate member 61 of the housing member 58 secured to the extensible beam member 43. The cylinders 96 and 101 are provided with suitable fluid supply lines 104, 105, 106 and 107, which

are connected to a suitable source of fluid under pressure, having suitable controls for selectively actuating the piston members 99 and 103 to move the beam members 44 and 43 laterally.

5 The unit also is provided with a second pair of fluid actuated devices 108 and 109 which interconnect the housing member 30 and the housing members 58 secured to the ends of extensible beam members 52 and 53. The fluid actuated devices 108 and 109 also are connected to 10 a source of fluid under pressure, having suitable controls for actuating the piston members thereof selectively to move the extensible beam members 52 and 53 laterally. The operation of the fluid actuated devices 94 and 108 is coordinated so that the extensible beam members 44 and 52 are moved in unison to extend the outrigger beam member 55 interconnecting the ends thereof. Similarly, the operation of the fluid actuated devices 95 and 109 is coordinated to move the outrigger beam member 56 outwardly to selected extended positions.

15 20 The operation of the stabilization unit is as follows. After the crane apparatus has been positioned, the outrigger beam members 55 and 56 are moved to the extended position, either individually or simultaneously by actuating the fluid actuated devices 94, 95, 108 and 109. When 25 the outrigger beam members 55 and 56 are in position, the fluid devices 54 are actuated so that the outrigger beam members 55 and 56 are moved downwardly until the wheeled units 57 engage the ground or any other support surface exterior of the vehicle. Whenever it becomes 30 necessary to move the crane apparatus while a load is being carried by the boom, the vehicle can be moved without disturbing the position of the outrigger beam members 55 and 56. It will be appreciated that when moving the vehicle, the wheeled units 57 will permit the entire 35 apparatus to be moved without retracting the stabilization unit.

It further will be appreciated that the outrigger beam members 55 and 56 can be independently adjusted vertically to compensate for sloping or uneven terrain. Also, 40 it would be possible to operate the fluid devices mounted on the ends of the extensible beam members 52 and 53 to lift the forwardly disposed wheeled units to permit the entire apparatus to be turned when it is desirable to move to a new position while the crane is carrying a load. 45 During such turning maneuvers it will be appreciated that a substantial amount of stabilization is maintained by means of the rearwardly disposed wheeled units being in positive engagement with ground surface.

The stabilization unit is retracted from its extended 50 position similarly by reversing the aforementioned operation. The fluid devices 54 are suitably actuated to lift the outrigger beam members 55 and 56 and the fluid devices 94, 101, 103 and 109 are actuated to move the outrigger beam members inwardly. The stabilization 55 unit is then held clear of the ground surface or any of the operating mechanisms of the crane apparatus, to permit the vehicle to be operated without any interference.

The stabilization unit can be constructed by any suitable 60 method, utilizing any suitable materials. It is preferred, however, that the unit be of a welded construction.

From the foregoing detailed description it will be evident that there are a number of changes, adaptations and modifications of the present invention which come within 65 the province of those skilled in the art. However, it is intended that all such variations not departing from the spirit of the invention be considered as within the scope thereof as limited solely by the appended claims.

70 75 What I claim is:

1. A stabilizer unit for a mobile crane apparatus and the like comprising a pair of laterally and horizontally extensible members mounted on each side of said apparatus, longitudinally disposed means mounted on the ends of said extensible members, wheeled units engageable

with a support surface exterior of said apparatus mounted on the ends of said longitudinally disposed means, first fluid actuated means for laterally displacing said extensible members and second fluid actuated means operatively interconnecting the ends of said extensible members and the ends of said longitudinally disposed means adjacent said wheeled units for displacing selectively said wheeled units vertically into and out of engagement with said support surface.

2. A stabilizer unit for a mobile crane apparatus and the like comprising a pair of housings mounted on said apparatus each having a pair of adjacent transversely disposed channels, each housing having a pair of transversely extensible beams mounted for transverse movement in said channels, first fluid actuated means mounted on said apparatus for displacing said extensible beams transversely, longitudinally disposed outriggers having the ends thereof mounted on the ends of said extensible beams, each of said outriggers having wheeled units mounted on the ends thereof engageable with a support surface exterior of said apparatus, second fluid actuated means mounted on the ends of said extensible beams operatively connected to the ends of said outriggers for displacing selectively said wheeled units vertically into and out of engagement with said support surface.

3. A support unit for a vehicle mounted crane apparatus and the like comprising a support frame mounted on said vehicle for mounting said crane apparatus, a pair of laterally and horizontally extensible members mounted on each side of said vehicle, longitudinally disposed means mounted on the ends of said extensible members, wheeled units engageable with a support surface exterior of said apparatus mounted on the ends of said longitudinally disposed means, first fluid actuated means for laterally displacing said extensible members and second fluid actuated means operatively interconnecting the ends of said extensible members and the ends of said longitudinally disposed means adjacent said wheeled units for displacing selectively said wheeled units vertically into and out of engagement with said support surface.

4. A support unit for a vehicle mounted crane apparatus and the like comprising a support frame mounted on said vehicle for mounting said crane apparatus, a pair of housings mounted on said vehicle each having a pair of transversely disposed channels, each housing having a pair of transversely extensible beams mounted for transverse movement in said channels, first fluid actuated means mounted on said vehicle for displacing said extensible beams transversely, longitudinally disposed outriggers having the ends thereof mounted on the ends of said extensible beams, each of said outriggers having

wheeled units mounted on the ends thereof engageable with a support surface exterior of said vehicle, second fluid actuated means mounted on the ends of said extensible beams operatively interconnected to the ends of said outriggers adjacent said wheeled units for displacing selectively said wheeled units vertically into and out of engagement with said support surface.

5. A mobile crane apparatus comprising a vehicle, a crane assembly mounted on said vehicle, a pair of laterally and horizontally extensible members mounted on each side of said vehicle, longitudinally disposed means mounted on the ends of said extensible members, wheeled units engageable with a support surface exterior of said apparatus mounted on the ends of said longitudinally disposed means, first fluid actuated means for laterally displacing said extensible members and second fluid actuated means operatively interconnecting the ends of said extensible members and the ends of said longitudinally disposed members adjacent said wheeled units for displacing selectively said wheeled units vertically into and out of engagement with said support surface.

6. A mobile crane apparatus comprising a vehicle, a crane assembly mounted on said vehicle, a pair of housings mounted on said apparatus each having a pair of adjacent transversely disposed channels, each housing having a pair of transversely extensible beams mounted for transverse movement in said channels, first fluid actuated means mounted on said vehicle for displacing said extensible beams transversely, longitudinally disposed outriggers having the ends thereof mounted on the ends of said extensible beams, each of said outriggers having wheeled units mounted on the ends thereof engageable with a support surface exterior of said vehicle, second fluid actuated means mounted on the ends of said extensible beams operatively connected to the ends of said outriggers for selectively displacing said wheeled units vertically into and out of engagement with said support surface.
